TERMINAL PLUG

Elmer E. Granger, Reno, Nev.

Original application August 15, 1944, Serial No. 549,611. Divided and this application September 4, 1945, Serial No. 614,376

1 Claim. (Cl. 173—361)

1

This invention relates to an electric outlet plug and constitutes a division from my copending application for patent upon an electric outlet box filed August 15, 1944, Serial No. 549,611, now Patent No. 2,423,016, issued June 27, 1947.

One object of the invention is to provide a plug having contact strips projecting from side portions thereof and serving as means for retaining the plug in operative engagement with an outlet box as well as for engaging bus bars in the box and causing power to be delivered to an electrical appliance from which leads feed wires to which the plug is attached.

Another object of the invention is to provide a plug so formed that when it is thrust into an outlet box through an opening in the front wall thereof it must be turned and disposed transversely of the opening in order to make contact with the bus bars or strips in the box.

Another object of the invention is to provide a plug having its contact strips so located that they will be disposed radially of the shank of the plug in such positions that screws for holding wires to the strips may be very easily unscrewed for application of the wires to them and then easily tightened.

Another object of the invention is to provide a plug which is simple in construction and not liable to be easily broken if the plug should be dropped upon a floor.

The invention is illustrated in the accompanying drawings wherein:

Figure 1 is a view showing plugs of the improved construction in elevation and engaged in an outlet box shown in longitudinal section.

Figure 2 is a view showing the outlet box partially in longitudinal section with a plug of the improved construction engaged therein.

Figure 3 is a view looking at the inner end of the plug.

Figure 4 is a sectional view taken longitudinally through the plug.

The outlet box shown in Figures 1 and 2 is of the construction shown in the copending application, referred to above, and has a casing 1 which fits into a wall box 2 where it is secured by an anchoring strip 3. A cover plate or block 4 formed of insulation is held in closing relation to the casing 1 by screws 5 and this plate or block has been shown formed with a pair of openings 6, each of which has its midportion 6' enlarged to form a substantially circular passage midway the length of the opening. While two openings 6 have been shown in the block or plate it will be understood that one opening or as many openings as desired

2

may be provided. The usual cover plate 7 is provided and formed with an opening through which the openings 6 are exposed. Bus strips 8 extend longitudinally in the casing with tongues 9 projecting through side walls of the casing and certain of the tongues carry screws 10 for connecting power wires 11 with the bus strips.

It will be understood that the plugs constituting the subject matter of this invention may be used 10 in connection with any wall box including a casing having bus strips extending longitudinally therein adjacent its side walls and a closure block for the casing formed with openings extending longitudinally of the block and having enlarged intermediate portions.

The improved plugs are formed as shown in Figures 1, 3, and 4 and each plug 12 has a shank 13 formed with a head or finger hold 14 at its outer end. The shank is circular in cross section and of 20 such diameter that it may be passed through the enlarged intermediate portion 6' of an opening 6 in the block 4 and fit snugly thereon. Contacts 15 are carried by the shank at opposite sides thereof. The contacts are formed from strips 25 of conductive metal and have their rear ends secured to the shank by screws 16. The metal strips are bent to form U-shaped arms which project radially from the shank and have their front ends free and carrying screws 18 by which 30 wires 19 of an electric cord 20 are secured to the contact strips 15. The electric cord passes through a bore or passage 21 formed longitudinally of the plug, and at the front end of the shank are formed notches 22 through which the 35 wires 19 pass.

When the plug is applied to the outlet box, its shank is thrust inwardly through the opening 6 with the shank fitting snugly in the enlarged portion of the opening and the contact strips 15 40 passing through end portions of the opening. The plug is then turned a quarter turn and, when one of the arms 17 engages the stop 23 extending downwardly from the inner face of block 4, the arms 17 will be disposed transversely of the 45 casing and their resiliency will cause them to frictionally bear against the under face of the cover plate or block 4 and prevent the plug from accidentally turning towards a position longitudinally of the casing in which the plug may move outwardly through the opening in the block. The fact that the contact strips are formed of 50 resilient metal also causes them to have binding engagement with the bus strips and since they engage the bus strips in spaced relation to 55 fulcrums 24 projecting from side walls of the

casing and engaged by midportions of the bus strips, the bus strips will be flexed somewhat and additional binding created between the contact strips and the bus strips. Since the plugs must be thrust into the casing and then turned in order to make contact between the arms 17 and the bus strips, the plugs may not slip outwardly and drop from the wall box or become disengaged from the bus strips to such an extent that arcing will occur and cause a fire to be started. When the plug is to be removed a reverse turn is imparted to it until turning motion is again stopped by contact of an arm 17 with the stop 23 and outward pull exerted to withdraw the plug from the wall box.

Having thus described the invention, what is claimed is:

A plug for an electric cord comprising an elongated body of insulating material circular in cross section and formed with a longitudinally extending bore constituting a cord passage, the rear end of said body being formed with a turning head of greater diameter than the body and the front end of the body being formed with diametrically opposed recesses leading from the bore end constituting aligned wire-receiving notches at opposite sides of the front end of the body, and contacts projecting radially from said opposite side portions of said body and located

between the head and the rear ends of said wire-receiving notches and spaced from the said head and the notches, each contact being formed from a strip of resilient metal bent to form a flat bridge constituting the outer end of the contact and front and rear arms extending from front and rear edges of the bridge towards the body, the rear arm being formed with a rearwardly projecting foot firmly secured to the portion of the body between the rear arm and the head, and the front arm being free from the body and spaced from the body and carrying a wire-securing screw engaged through a threaded opening formed in the arm.
